SAFETY SWITCH MECHANISM

Filed June 2, 1921

2 Sheets-Sheet 2

UNITED STATES PATENT OFFICE.

JOHN R. KELLEY, OF COVINGTON, KENTUCKY.

SAFETY SWITCH MECHANISM.

Application filed June 2, 1921. Serial No. 474,464.

An object of my invention is to provide a switch mechanism adapted to preclude initial overloading of a motor.

Another object is to provide a switch mechanism for the purpose stated adapted to preclude closing of the circuit embracing the motor unless the motor has been conditioned for the running current to be supplied thereto.

Another object is to provide a switch mechanism for the purposes stated that will automatically lock the mechanism against closing of the circuit unless the switch mechanisms are in their proper or normal relation before starting the motor.

Another object is to provide a device for the purposes stated that is simple in operation and construction and that is practically fool proof.

These and other objects are attained by the means described herein and disclosed in the accompanying drawings, in which

Fig. 1 is a fragmental side elevation of a frame having mounted upon it a switch mechanism embodying my invention.

Fig. 2 is an end elevation of some of the parts shown in Fig. 1.

Fig. 3 is an enlarged sectional view on line 3—3 of Fig. 1.

Fig. 4 is an enlarged perspective view of a spring latch forming a detail of my invention.

Fig. 5 is a diagrammatic view of the wiring of the switch and the motor and showing a modified construction of the parts shown in Fig. 3.

My invention comprises a control switch A shunted across the line wires b and b' adapted to be locked against the closing of the circuit embracing itself and the operating switch D when the operating switch is in any position other than that which it should assume when a motor M is to be first energized or started.

The control switch A comprises a housing a mounted upon the frame C and containing a sleeve a' of some non-magnetic material, such as brass, about which is disposed an electric winding a² adapted with the magnetic core a³ disposed within the sleeve a' to form an electro-magnet. The core a³ has a central bore a⁴ thru which extends a reciprocating rod a⁵ having mounted upon it an armature a⁶ adapted to be attracted by the core a³ when energized. A non-magnetic collar a⁷ is mounted upon the rod a⁵

adjacent one end thereof, which end extends thru the frame C and has mounted upon it a suitable handle or knob a⁸ whereby the rod a⁵ may be longitudinally reciprocated in the sleeve. A suitable key a⁹ may be employed to preclude rotatory motion of the rod a⁵. A block a¹⁰ upon which the housing is mounted, spaces the forward end of the housing from the rear of the frame C. A metallic ring a¹² of magnetically responsive material spaces the rear end of the sleeve from the rear end of the housing. A block a¹¹ mounted on the housing and thru which the rod a⁵ extends, has mounted upon it a metallic band a¹³ having a conical face. The metallic band is electrically connected with the operating switch in a manner which will be more fully explained hereafter. The rear end of the rod a⁵, or in other words the end spaced from the knob a⁸, has mounted upon it a block a¹⁴ of insulating material upon which is mounted the spring contact arms a¹⁵ adapted to make an electrical connection with the conical face of the metallic band a¹³. Normally the arms a¹⁵ do not engage the metallic band, and when the arms are moved into contact with said band, the arms are tensioned so that when the force that held the arms in contact upon the ring has been withdrawn, the tendency of the spring arms to assume their normally unstrained positions causes the rod a⁵ to be moved longitudinally in such direction that the arms a¹⁵ are disengaged from the metallic band a¹³.

The spring contact arms are electrically connected with a conductor post a¹⁶ mounted upon the block a¹⁰ adjacent the housing a by means of a flexible conductor a¹⁷. The core a³ and the armature a⁶ bear such relation that when the electro-magnet is energized, the contact arms a¹⁵ will move into engagement with the metallic band a¹³ and the armature a⁶ will assume a position in immediate proximity to the core and will be retained in such position by the magnetic attraction of the core against the yielding resistance of the spring arms a¹⁵. The winding a² of the electro-magnet is electrically connected with the metallic band a¹³ and with the return wire b'. 100

A source of electrical supply B, represented as a battery, has one of its poles connected with feed line wire b and its other pole connected with return line wire b'. 110 The line wire b is electrically connected with the conductor post a¹⁶. The current passing

through the line wire b and through the control switch A passes to the operating switch D by way of the wire b^2 .

The operating switch D is mounted upon an insulating bracket c formed on the frame C. The wire b^2 is electrically connected with contact d mounted upon the bracket c and the return wire b' is electrically connected with a contact d' mounted upon the bracket c adjacent the contact d . A conductor bar d^2 is pivotally mounted upon the contact d and a conductor bar d^3 is pivotally mounted upon the contact d' , the conductor bars being attached to an insulating connector rod d^4 . Each conductor bar comprises a starting arm d^5 and a running arm d^6 . The starting arms of the bars d^2 and d^3 are disposed upon the same side of the connector d^4 and have mounted upon them the contact buttons d^7 adapted to be moved into engagement with the starting contact buttons d^8 mounted upon the springs d^9 , connected with the opposite terminals of a motor M. Suitable resistances E are interposed between the contacts d^8 and the motor terminals. The running arms d^6 of the bars are adapted to be moved into engagement with the running contacts d^{10} , connected with opposite terminals of the motor M. The contacts d and d' are disposed intermediate the starting contacts d^8 and running contacts d^{10} in such relation that when the motor has been started by means of passing the current through the starting arms and the starting contacts, and then the conductor bars are actuated about their pivotal mountings so as to break the circuit through the starting contacts d^7 and d^8 and to re-establish a circuit through the running arms d^6 and running contacts d^{10} , the current will follow the same path through the motor M. A revoluble shaft d^{11} is mounted upon the frame C and extends therethrough and has its axis in alignment with the axes of the pivots mounting the conductor bars upon the contacts d and d' . A crank d^{12} mounted upon the shaft d^{11} adapted to be revolvably actuated thereby, is secured to the insulating connector d^4 whereby rotatory motion of the shaft d^{11} may be imparted to the bars d^2 and d^3 . A spring d^{13} is coiled about the shaft d^{11} and yieldingly retains the running arms of the bars in engagement with the running contacts d^{10} . An arm d^{14} is mounted upon the crank d^{12} in substantial alignment with the connector d^4 and extends toward the frame C. A radial lug d^{15} of a substantially triangular cross section is formed on the arm d^{14} and is adapted to engage a spring latch F. A collar d^{16} is mounted upon the shaft d^{11} and has a mutilated edge whereby a flat face d^{17} is formed upon its outer edge. A suitable handle d^{18} is mounted upon the end of the shaft d^{11} extending through the frame C. The collar d^{16} and the handle d^{18}

precludes longitudinal movement of the shaft d^{11} .

The spring latch F comprises a spring arm f mounted at one of its ends upon the frame C and having mounted upon its other end a catch f' . The spring arm f and the catch f' extend in substantial parallelism with the bracket c supporting the conductor bars. The end of the catch f' adjacent the starting contacts d^8 is developed into a knife edge f^2 having an angular face f^3 extending from the knife edge toward the frame C. The other end of the catch f' or in other words the end of the latch disposed adjacent the running contacts d^{10} , is developed into a substantial knife edge f^4 having its angular face f^5 disposed on the side of the latch opposite to the face f^3 , the face f^5 being substantially parallel with face f^3 . A notch or pocket f^6 is formed in the catch f' intermediate its ends and upon that side of the catch adjacent the conductor bars. The spring arm f is adapted to hold the catch f' in the path of the lug d^{15} . The lug d^{15} has a forward knife edge d^{16} adapted to engage the face f^5 when the shaft d^{11} is actuated to disengage the running arms d^6 and running contacts d^{10} , and a rear knife edge d^{20} adapted to engage the face f^3 on the catch f' when the shaft d^{11} is actuated so as to separate the starting button contacts d^7 and d^8 . The lug is also adapted to engage in the notch or pocket f^6 formed upon the catch. The face d^{21} formed on the lug adjacent the knife edge d^{20} is adapted to engage the face f^3 on the latch as the lug moves by the catch and the face d^{22} formed on the lug intermediate the knife edges d^{16} and d^{20} thereon is adapted to engage the face f^5 on the catch as the lug d^{15} is moved toward the pocket f^6 in the catch.

A locking arm H is mounted intermediate its ends upon a pivot G mounted upon the frame C. One end of the arm H is adapted to engage the collar d^{16} mounted on the shaft d^{11} , and the other end is adapted to be moved intermediate the collar d^{16} mounted on the rod a^5 and the frame C and to thereby preclude longitudinal movement of the rod a^5 toward the frame C, wherefore it is impossible to make an electrical contact between the spring contact arms a^{15} and the metallic band a^{13} . A spring h normally retains the locking arms H in engagement on the collar d^{16} . The face d^{17} formed on the collar d^{16} is disposed at such a place that when the arms d^8 of the conductor bars engage the contacts d^{10} , said face d^{17} will be exposed to the rod H and may be contacted by the rod H.

The control switch A described is adapted to control electrical communication between the wires b and b^2 , or in other words is a one pole switch.

In Fig. 5 is shown a double pole control

switch. In this construction the metallic band is formed in two pieces a^{18} and a^{19} that are insulated from one another and each of which is adapted to make an electrical connection with one of the spring arms a^{15} , of which one is connected with the feed wire b and the other is connected with the return wire b' . In this construction the key a^9 precludes relative rotary motion of the rod a^5 and the metallic band sections, wherefore the direction of the flow of current will not be modified by the control switch. It is also necessary in this construction to provide two conductor rods a^{16} and two flexible metallic connectors a^{17} .

A suitable line switch L is interposed between the source of electrical supply B and the control switch A .

The operation of my device is as follows: We will assume that the parts are in the relation shown in Fig. 1, the spring contact arms a^{15} being in the positions shown in full lines in Fig. 3. The handle a^8 is then pulled away from the frame C to a position as shown in dotted lines in Fig. 3, thereby causing the spring contact arms a^{15} to engage the metallic band a^{13} and energizing the electro-magnet contained within the housing a , wherefore the armature a^6 will be retained in such position by the magnetized core a^8 , that the spring arms a^{15} will remain in contact with the metallic band a^{13} . The handle d^{18} is then revolved in such direction that the button contacts d^7 are brought into engagement with the button contacts d^8 thereby completing a starting circuit embracing the resistances E and the motor M . The engagement of lug d^{15} in pocket f^6 precludes any other movement of the handle d^{18} . After the motor armature has begun to revolve, the operator releases the handle d^{18} , whereupon the spring d^{13} moves the conductor bars about their pivotal mountings and cause the arms d^6 thereon to engage the contacts d^{10} , wherefore the motor is embraced in a full load circuit. As the spring d^{13} moves the conductor bars about their pivotal mountings, the knife edge d^{20} and the face d^{21} on the lug d^{15} engage and pass over the face f^2 on the catch f' , the spring arm f permitting movement of the catch f' towards the conductor bar d^3 . When the running arms d^6 engage the running contacts d^{10} , the face d^{17} formed on the collar d^{16} is exposed to the arm H .

We will now assume that the line switch L is opened, wherefore the electro-magnet in the control switch is de-energized, and the action of the spring arms a^{15} causes the rod a^5 to be moved longitudinally to such extent that the contact between the spring contact arms a^{15} and the metallic band a^{13} is broken. This movement of the rod a^5 serves to move the collar a^7 away from the frame C , whereupon the end of the arm H , which was being

held in engagement with the collar a^7 by means of the spring h , is separated from the collar a^7 , wherefore the spring h moves the arm H about its pivotal mounting G and causes the arm H to engage upon the face d^{17} formed on the collar d^{16} . When the arm H is in this position the end thereof adjacent the control switch assumes a position intermediate the collar a^7 and the frame C , wherefore it is impossible to move the rod a^5 to such extent as to again move the spring contact arms a^{15} into engagement with the metallic band a^{13} .

From the foregoing it will be readily apparent that the only way in which it will be possible to again energize the motor will be by revolubly actuating the shaft d^{11} by means of the handle d^{18} and to thereby cause the arm H to be moved from the position it now assumes intermediate the collar a^7 and the frame C . When the handle d^{18} is moved in the proper direction for the purpose stated, the knife edge d^{19} and the face d^{22} formed on the lug d^{15} engage and pass over the face f^5 on the catch f' , thereby moving the catch away from the conductor bar d^3 . When the lug d^{15} has been moved over the face f^5 of the catch f' against the yielding resistance of the spring arm f , the catch is moved toward the bar d^3 , whereupon the handle d^{18} may be released and the lug d^{15} will engage in the pocket f^6 in the catch, and the parts will again be in the position shown in Fig. 1.

What I claim is:

1. In a device of the class described the combination of an operating switch comprising a starting contact, a running contact, a conductor bar adapted to assume positions in engagement with the contacts and a position spaced from the contacts, a control switch comprising normally disengaged contacts, one of which is electrically connected with the conductor bar, and the other of which is electrically connected with a source of electrical energy, means adapted to move the contacts of the control switch into engagement with one another, and means to preclude movement of the contacts of the control switch from their normal positions by the contact moving means when the conductor bar is in engagement with the running contact.

2. In a device of the class described the combination of an operating switch comprising a starting contact, a running contact, a conductor bar adapted to assume positions in engagement with the contacts and a position spaced from the contacts, a control switch comprising normally disengaged contacts, one of which is electrically connected with the conductor bar and the other of which is electrically connected with a source of electrical energy, means adapted to move the contacts of the control switch into

engagement with one another, means to preclude movement of the contact moving means when the conductor bar is in engagement with the running contact, and means adapted to render the locking means inoperative when the conductor bar is spaced from the starting and running contacts.

3. In a device of the class described the combination of an operating switch comprising a starting contact, a running contact, a conductor bar adapted to assume positions in engagement with the contacts, and a position spaced from the contacts, a control switch comprising normally disengaged contacts, one of which is electrically connected with the conductor bar and the other of which is connected with a source of electrical energy, a reciprocating rod adapted to move the contacts of the control switch into engagement with one another, and a locking arm adapted to lock the reciprocating rod against movement from its normal position when the conductor bar is in engagement with the running contact.
- 25 4. In a device of the class described the combination of an operating switch comprising a starting contact, a running contact, a conductor bar adapted to assume positions in engagement with the contacts, and a position spaced from the contacts, a control switch comprising normally disengaged contacts, one of which is electrically connected with the conductor bar and the other of which is connected with a source of electrical energy, a reciprocating rod adapted to move the contacts of the control switch into engagement with one another, a locking arm adapted to lock the reciprocating rod against movement from its normal position 30 when the conductor bar is in engagement with the running contact, and means to release the reciprocating rod from the locking arm when the conductor bar is spaced from the contacts.
- 45 5. In a device of the class described the combination of an operating switch comprising a starting contact, a running contact, a conductor bar adapted to assume positions in engagement with the contacts and 50 a position spaced from the contacts, a control switch comprising normally disengaged contacts, one of which is electrically con-

nected with the conductor bar and the other of which is connected with a source of electrical energy, means to move the contacts 55 of the control switch into engagement with one another, means to retain the last mentioned contacts in engagement with one another, and means adapted to space the last mentioned contacts when released from the 60 retaining means.

6. In a device of the class described the combination of an operating switch comprising a starting contact, a running contact, a conductor bar adapted to assume positions 65 in engagement with the contacts and a position spaced from the contacts, a control switch comprising normally disengaged contacts, one of which is electrically connected with the conductor bar and the other of 70 which is connected with a source of electrical energy, means to move the contacts of the control switch into engagement with one another, means to retain the last mentioned contacts in engagement with one 75 another, means adapted to space the last mentioned contacts when released from the retaining means, and means adapted to preclude movement of the control switch contacts into engagement with one another 80 when the conductor bar is in engagement with the running contact.

7. In a device of the class described the combination of an operating switch comprising a starting contact, a running contact, a conductor bar adapted to assume a position in engagement with the contacts and a position spaced from the contacts, a control switch comprising normally disengaged contacts, one of which is electrically connected 85 with the conductor bar and the other of which is connected to a source of electrical energy, means to move the contacts of the control switch into engagement with one another, means to retain the last mentioned 90 contacts in engagement with one another, and means controlled from the operating switch for spacing the contacts of the control switch when the said contacts are released.

In testimony whereof, I have hereunto subscribed my name this 31st day of May, 1921.

JOHN R. KELLEY.
